LIGHTING DEVICE

Hans Hacklander, Linden, N. J., assignor to The Singer Manufacturing Company, Elizabeth, N. J., a corporation of New Jersey

Original application September 2, 1939, Serial No. 293,155. Divided and this application December 6, 1939, Serial No. 307,725

9 Claims. (Cl. 112—218)

This invention relates to a lighting device and more particularly to a lighting device for use with so-called cup-feed sewing machines.

In a sewing machine of the cup-feed type wherein the stitch-forming instrumentalities, feed-cups and usually a fabric uncurling guide are necessarily crowded into a relatively small space, it is decidedly advantageous to have a sufficient amount of light directed to the vicinity of the stitching point so that the operator may observe the character of the stitching and the position of the work as it passes through the machine, and also so that the various stitching implements, such as the needle and looper, may be more conveniently threaded.

It is the primary object of the present invention to provide in a cup-feed sewing machine of the hosiery seaming type a lighting device so disposed that it will not encroach upon the area adjacent the stitching point required for work-handling, and at the same time will direct a sufficient amount of light to the vicinity of the stitching point to assist the operator in producing work of a high quality.

Another object of the invention is the provision in a cup-feed sewing machine of a built-in lighting device, as distinguished from an attachment adapted to be fastened externally of the machine-frame.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a right side elevation of a sewing machine embodying the invention with portions of the bottom cover-plate and the standard-wall of the frame broken away to show the way in which the tubular conduit for the electrical conductor is secured in the bottom cover-plate.

Fig. 2 is a front elevation of the upper portion of the sewing machine illustrating the location of the incandescent lamp with respect to the stitch-forming devices.

Fig. 3 is a top plan of the machine with a portion of the top-cover-plate broken away to show the mounting for the lamp-socket.

In the embodiment of the invention selected for illustration my lighting device is shown as applied to a so-called cup-feed sewing machine

having a frame including a standard 1 terminating at its upper end in a laterally projecting overhanging bracket 2. As more fully described in my copending application Serial No. 293,155, filed September 2, 1939, of which this application is a division, the standard 1 at its upper end is formed with a horizontal partition 3 which divides the machine-frame into a splash-lubrication compartment 4 and a belt-compartment 5. The splash-lubrication compartment 4 is closed at the bottom by means of a plate 6 secured by screws 7 and sealed by a gasket 8.

Externally of the machine-frame and beneath the overhanging bracket 2 are the stitch-forming devices including a needle 9, a looper 10 and a second looper or spreader 11 which cooperate in timed relation to produce overedge stitches in fabric sections supported and advanced past the stitching point by the driven feed-cups 12 and 13. The needle 9 is carried in the exposed end of an endwise reciprocatory needle-bar 9' journaled horizontally in the machine-frame. The looper 10 and the spreader 11 are fixed in the free ends of the horizontal divergent rock-shafts 10' and 11', respectively, which, as shown in Fig. 2, penetrate the machine-frame at points on opposite sides of the vertical plane containing the axis of the needle-bar 9'. The mechanisms within the frame employed for operating the needle-bar 9', the looper rock-shaft 10' and the spreader rock-shaft 11' are fully disclosed in my copending application Serial No. 293,155 above referred to. The arrangement of the looper and spreader rock-shafts or supporting members on opposite sides of the vertical plane containing the axis of the needle-bar is advantageous in that there is provided a space directly above the needle-bar which is free of mechanism and into which may be put a lighting device adapted to illuminate a substantial area at the stitching point without casting any objectionable shadows on the work, or shining into the eyes of the operator.

It will be observed in Fig. 1 that the bottom plate 6 of the standard 1 is formed with a boss 14 apertured to receive a tubular conduit 15 of such external diameter as to be a press-fit in the boss 14. The tubular conduit 15 at its upper end extends into the belt-compartment 5 through a clearance aperture 16 formed in the horizontal partition 3. Passing through the tubular conduit 15 is a regular insulated electrical conductor 17, the tubular conduit 15 acting as a protecting sheath or guard for the conductor 17 and preventing its contact with the oil in the splash-lubrication compartment 4. The

insulated covering for the electrical conductor 17 is preferably composed of an oil-repellent material, such as "neoprene," so that all likelihood of the electrical conductor being deleteriously affected by the oil-laden mist within the machine-frame will be eliminated. The upper end of the electrical conductor 17 is connected to a conventional lamp-socket 18 which is secured, preferably by means of a clamp or strap 19 held in place by a screw 20, on a suitable pad 20' interposed between the lamp-socket 18 and an inclined concave seat 21 formed in a cavity 22 provided in the wall of the machine-frame substantially at the junction of the standard 1 and the overhanging bracket 2. Detachably secured in the socket 18 is a low-voltage incandescent lamp 23, the free end of which is disposed outside of the wall of the machine-frame and beneath the overhanging bracket 2. To prevent or minimize glare from the lamp the upper portion thereof can be suitably painted or otherwise shaded.

As clearly shown in Fig. 1, the lower portion of the boss 14 on the bottom plate 6 is countersunk, as at 24, and threaded to receive the conventional clamp 25 for the flexible BX covering 26 which protects the insulated conductor 17.

It will be evident from the drawings that the incandescent lamp is located above all the stitch-forming devices and adjacent the wall of the machine-frame so that it will not encroach upon the area adjacent the stitching-point required for work-handling. The design of the lighting device is extremely simple and lends itself to convenient installation in a machine of the type illustrated.

While I have illustrated and described a preferred embodiment of the invention, it will be understood that the form, construction and arrangement of the elements employed may be varied, and the privilege is reserved of resorting to all such legitimate changes therein as may be fairly embodied within the spirit and scope of the appended claims.

Having thus set forth the nature of the invention, what I claim herein is:

1. In a sewing machine, a frame including a standard terminating in a laterally projecting overhanging bracket, feed-cups exteriorly of said frame and disposed beneath said overhanging bracket for supporting and feeding fabric sections, stitch-forming instrumentalities including a needle and at least one complemental element located above said feed-cups for forming stitches in said fabric sections, an endwise reciprocatory needle-bar carrying said needle, a cavity in said frame at the junction of the overhanging bracket and the standard above the level of the stitch-forming instrumentalities, a lamp-socket fixed in said cavity, and an incandescent lamp secured in said socket and disposed substantially vertically above said needle-bar for illuminating a substantial area in the vicinity of the stitching point.

2. In a sewing machine, a frame including a standard and a laterally projecting overhanging bracket, feed-cups exteriorly of said frame and disposed beneath said overhanging bracket for supporting and feeding fabric sections, stitch-forming instrumentalities located above said feed-cups for forming stitches in said fabric sections, a cavity in said frame at the junction of the overhanging bracket and the standard and above the level of the stitch-forming instrumentalities, a lamp-socket arranged within said cav-

ity and contacting one wall thereof, a clamp bearing upon said lamp-socket for maintaining the latter in fixed position, and an incandescent lamp secured in said socket for illuminating a substantial area in the vicinity of the stitching point.

3. In a sewing machine, a frame having a splash-lubrication compartment formed therein, a conduit within said frame and extending through said splash-lubrication compartment, an electrical conductor within said conduit and sealed thereby from contact with oil in said splash-lubrication compartment, a lamp-socket connected to said electrical conductor and secured to said frame, and an incandescent lamp mounted in said socket and projecting externally of said frame for directing a light beam to a point exteriorly of said frame.

4. In a sewing machine, a frame including a standard and an overhanging bracket, a splash-lubrication compartment in said standard, a compartment in said overhanging bracket separated from said lubrication compartment, a plate adapted to close said splash-lubrication compartment, a conduit secured to said plate and extending through said splash-lubrication compartment and into the compartment in said bracket, a lamp-socket within said overhanging bracket, an electrical conductor passing through said conduit and connected to said lamp-socket, and an incandescent lamp mounted in said socket and projecting externally of the frame for illuminating a substantial area exteriorly of the frame.

5. In a sewing machine, a frame including a standard and a laterally projecting overhanging bracket, feed-cups exteriorly of said frame and disposed beneath said overhanging bracket for supporting and feeding fabric sections, stitch-forming instrumentalities above said feed-cups including a needle and a plurality of complemental thread-handling implements, an endwise reciprocatory needle-bar journaled horizontally in said frame, supporting members for said thread-handling implements each disposed to one side of the vertical plane containing the axis of said needle-bar, and an incandescent lamp secured to said frame vertically above said needle-bar and substantially at the junction of the standard and overhanging bracket for illuminating a substantial area in the vicinity of the stitching point.

6. In a sewing machine, a frame including a standard and a laterally projecting overhanging bracket, feed-cups exteriorly of said frame and disposed beneath said overhanging bracket for supporting and feeding fabric sections, stitch-forming instrumentalities above said feed-cups including a needle and a plurality of complemental thread-handling implements, an endwise reciprocatory needle-bar journaled in said frame, supporting members for said thread-handling implements each disposed to one side of the vertical plane containing the axis of said needle-bar, a cavity formed in the wall of said frame vertically above the needle-bar, a lamp-socket secured in said cavity, an electrical conductor housed within said frame and connected to said lamp-socket for supplying electrical energy thereto, and an incandescent lamp in said socket and projecting externally of said frame for illuminating an area in the vicinity of the stitching point.

7. A cup-feed sewing machine having a frame including a standard and a laterally projecting overhanging bracket, an outer feed-cup sup-

ported from above by said overhanging bracket, an inner feed-cup supported from below by said standard, stitch-forming devices including a needle and a plurality of complementary thread-handling implements, a needle-bar reciprocable in said standard, supporting members for said thread-handling implements each disposed to one side of the vertical plane containing the axis of the needle-bar, and an incandescent lamp secured to said frame vertically above said needle-bar and beneath the overhanging bracket for illuminating a substantial area in the vicinity of the stitching point without reflecting or shining the light in the eyes of the operator.

8. In a sewing machine, a frame including a standard and a laterally projecting overhanging bracket, feed-cups exteriorly of said frame and disposed beneath said overhanging bracket for supporting and feeding fabric sections, stitch-forming instrumentalities above said feed-cups including a needle and at least one complementary thread-handling implement, an endwise reciprocating needle-bar horizontally journaled in said frame, a supporting member for said complementary thread-handling implement disposed horizontally and to one side of the vertical plane containing the axis of said needle-bar, an incandescent lamp secured to said frame vertically

above said needle-bar and substantially at the junction of the standard and the overhanging bracket, and an electrical conductor disposed within the walls of said frame and connected to said incandescent lamp for supplying energy thereto from an outside source.

9. A cup-feed sewing machine having a frame including a standard and an overhanging bracket, cooperating feed-cups, and stitch-forming devices 10 above said feed-cups, a partition within said frame defining with the walls of said standard a lubrication compartment and with the walls of said overhanging bracket a compartment separated from said lubrication compartment, a plate 15 adapted to close said lubrication compartment, a conduit extending through said lubrication compartment and having one end secured to said plate and the other end projecting through said partition into the compartment in said overhanging bracket, a lamp-socket fixed to said overhanging bracket above the stitch-forming devices, an electrical conductor passing through said conduit and sealed thereby from contact with oil in said lubrication compartment, and an incandescent lamp mounted in said socket in position to illuminate a substantial area in the vicinity of the stitching point.

HANS HACKLANDER.
